(57) **CLAIM**

The ornamental design for a frame for a photovoltaic panel array, as shown and described.

DESCRIPTION

FIG. 1 is a top front perspective view of a frame for a photovoltaic panel array showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top front perspective view thereof in an example environment.

The dashed broken lines in the figures show portions of the photovoltaic panel array and environment that form no part of the claimed design.

The dot-dash broken lines in the figures show boundaries that form no part of the claimed design.
